United States Patent Office.

J. L. VAN WERT, OF TOLLAND, MASSACHUSETTS.

Letters Patent No. 98,722, dated January 11, 1870.

IMPROVEMENT IN HORSE-COLLARS.

The Schedule referred to in these Letters Patent and making part of the same

To all whom it may concern:

Be it known that I, J. L. VAN WERT, of Tolland, Hampden county, State of Massachusetts, have invented a new and improved Horse-Collar; and I do hereby declare that the following is a full and clear description thereof, reference being had to the accompanying drawings, and to the letters of reference marked thereon.

In the drawings—

Figure I is a perspective view of my improved collar.

Figure II is a detailed cross-sectional view.

Figures III and IV are detail views of parts of the same.

My improved horse-collar is formed with a metal frame, A, to which the padding is attached, dispensing with hames, as the traces may be attached directly to the frame.

In the drawings, it is shown, in Fig. II, that the frame A is formed with a convex and concave side, the convex side having the padding on it, any suitable metal combining strength and lightness, steel or malleable iron, preferred.

It is not necessary to continue the frame much above the shoulder of the horse, as a good bearing-surface is all that is necessary in most cases.

The padding is usually stitched to the edges of the frame, the same being provided with thread-holes for that purpose. It is also provided with screw-holes, a, so that the necessary rings and hooks may be put on, in order to adapt the collar to different circumstances.

The collar is connected at the top by a neck-pad, B, which has on its ends, or one end, a T-shaped catch, C, hooks D being formed on the frame for it to hook in.

In Fig. III, two views are shown, illustrating the manner in which the parts are locked, part one showing the position in which the catch has to be placed in order to enter it, and part two showing an end view of the hooks, with the catch at rest in place, and also

an end view of it in the position shown in part first, the entrance of the hooks being made narrow at c, and the catch being made broadest at its resting side, which necessitates its being passed in edgewise. Once in place, the strain from the neck-pad keeps it properly in position; and, in order to get it out again, the motion has to be reversed, so that a secure fastening is obtained.

The method of fastening the trace is by means of a T-catch on the end of the trace, and a split cylinder, E, rigidly fastened to the collar-frame at the shoulder, in front.

This cylinder has notches, ff, cut in it from the central longitudinal slit g, for the shank of the catch to rest in, the number of these notches comprising a range covering all practical and useful adjustments, the catch being slid in from the end of the cylinder, and the shank set in the notch corresponding to the height required to set the trace.

Other methods of connecting both trace and neck-pad may be used with advantage, and I do not confine myself to any particular methods of constructing the auxiliary parts of the collar.

The collar thus formed is light, strong, and serviceable, and one frame will outlast many pads. No hames are required, as the traces may be attached and detached in the easiest manner.

Now, having described my invention,

What I claim as new, and desire to secure by Letters Patent, is—

The combination, in a horse-collar, of the padded arched metal frame A, the T-catches, for fastening the braces, the split cylinder E, having notches ff, and the hooks D, for attaching the neck-pad, by means of the T-hooks C, the whole constructed substantially as shown.

J. L. VAN WERT.
